UNITED STATES PATENT OFFICE

164,163

KNIFE HANDLE OR THE LIKE

Thomas S. Gorton, Chicago, Ill.

Application March 20, 1951, Serial No. 14,556

Term of patent 14 years

(Cl. D44—29)

To all whom it may concern:

Be it known that I, Thomas S. Gorton, a citizen of the United States, residing at Chicago, Illinois, have invented a new, original, and ornamental Design for a Knife Handle or the like, of which the following is a specification, reference being had to the accompanying drawing, forming a part hereof.

Referring to the drawing:

Fig. 1 is a perspective view of the knife handle;

Fig. 2 is a top view;

Fig. 3 is a side view; and

Fig. 4 is a bottom view thereof showing my new design.

I claim:

The ornamental design for a knife handle or the like, as shown.

THOMAS S. GORTON.
